UNITED STATES PATENT OFFICE.

ALVIN A. DAUGHERTY, OF LOS ANGELES, CALIFORNIA.

SACK.

1,190,221.

Specification of Letters Patent.

Patented July 4, 1916.

Application filed November 30, 1914. Serial No. 874,921.

To all whom it may concern:

Be it known that I, ALVIN A. DAUGHERTY, a citizen of the United States, residing at Los Angeles, in the county of Los Angeles, State of California, have invented a new and useful Sack, of which the following is a specification.

My invention relates to packages for containing finely comminuted materials, such as cements, plasters, or the like.

The principal object of the invention is to provide a package in which these finely divided or powdered materials may be packed and which will be of such a structure that this material will not sift through the meshes of the package as it is handled. This is accomplished by providing a composite package composed of a metallic cloth, the interstices of the cloth being filled by packing strands of fabric. A large proportion of the cement, plaster, lime, and the like now used is put up in cotton, jute, or similar sacks, these packages being handled many times before the contents thereof are finally used. In the handling of such packages a considerable proportion of the contents is lost by sifting through the meshes thereof and my package is especially designed to prevent this loss. Such packages are further subject to extremely rough usage and a further object of my invention is to provide a package which will be much more durable and consequently longer lived.

In the practical use of jute, cotton, or similar sacks it is found that a large loss occurs, due to the rotting of these sacks both during their use and while they are in storage. When these sacks have wholly or partially decayed they lose their tensile strength and are of no use whatever.

A further object of my invention is to provide a sack in which a metallic thread or wire is used for the purpose of giving the necessary tensile strength, cotton, jute, or other fabric threads being added to give greater flexibility, these fabric threads also serving as soft packing means between the wire members to form an impervious cloth.

A particular use for my improved package is found in the cement industry which is of large proportions, the annual expenditure for sacks for use in this industry in the United States reaching the figure of \$11,000,000. This is due to the rapid deterioration of ordinary cotton or jute sacks both from rough handling and from decay.

My invention is designed to greatly reduce this annual cost and thereby relieve the cement industry of this great burden.

In the practical handling of cement, plaster, and lime, it is extremely essential that the contents of the package be protected from water. It is also highly desirable that the contents be protected from the atmosphere which carries considerable moisture therein. A considerable loss results in the industries using these materials from the deterioration of the contents of the ordinary sacks due to the action of moisture thereon.

A further object of my invention is to produce a package which will be water proof.

My invention consists essentially of a package formed of a cloth containing both metallic and fabric threads. This cloth is so tightly woven that the fabric threads are compressed between the metallic threads making an almost impervious package.

My invention further consists in coating this fabric on one or both sides with a water proof enamel or varnish, this enamel or varnish permeating and impregnating the fabric strands and producing a water proof and durable package.

Further objects and advantages will be evident to one skilled in the art to which the invention pertains especially after reading the annexed specification and claims and inspecting the drawing which forms a portion thereof and which illustrates one embodiment only of the invention. The doctrine of equivalents should therefore be broadly applied in construing the claims illustrated by this drawing.

In the drawing, Figure 1 is a perspective view of a filled and sealed package. Fig. 2 is a greatly enlarged view of the fabric from which the package is formed without enamel. Fig. 3 is a section on the plane x^3-x^3 of Fig. 2 with the enamel coatings added.

The package may be of any desired shape, that shown in Fig. 1 being chosen for illustrative purposes only.

This sack consists of a body portion 11 and a closure 12. The cloth consists of metallic warp threads 13 and fabric warp threads 14 arranged alternately as shown in Fig. 2.

It consists further of metallic weft threads 15 and fabric weft threads 16 arranged alternately as shown in Fig. 2. It is obvious that the proportion of threads does not need to be absolutely that shown, and

that there may be two or more threads of one kind to each thread of the other kind if desired. In weaving the fabric great care is exercised to force the metallic members 5 13 and 15 closely together, the fabric members 14 and 16 being compressed therebetween and forming packing means. It is further evident that even after these fabric members have become greatly weakened by 10 decay that they will still serve as efficient packing means to prevent the filtration of material therethrough and that the metallic strands 13 and 15 will still furnish the necessary strength to the fabric. The metallic 15 strands are preferably of copper, or a copper alloy, but any material having the necessary characteristics may be used, galvanized iron, or a very pure iron may be used, or indeed any material which is flexible and durable. 20 For the purpose of further improving the package outer and inner layers of varnish or enamel 17 and 18 are applied to the fabric. This varnish or enamel adheres readily to the metallic members and permeates and 25 impregnates the fabric members so that the water and dust proof qualities of the sack are greatly improved thereby. The sack is closed by any of the standard means, such as by sewing as shown at 19 in Fig. 1. 30 While the first cost of a package using copper threads will be large there will be a large salvage due to the scrap value of the copper and the total cost of using such packages will be small, due partly to this salvage

and partly to the great durability of such 35 a package. Moreover such packages can be repaired with comparative ease by sewing or otherwise securing patches over torn or cut places.

I claim as my invention:

- 40 1. An imperforate sack formed of fabric and metallic members woven into a cloth.
2. An imperforate sack formed of fabric and copper wire members woven into a cloth. 45
3. An imperforate sack formed of fabric and metallic members woven into a cloth, and having a coating of enamel or varnish applied thereto.
4. An imperforate sack formed of fabric 50 and copper wire members woven into a cloth and having a coating of enamel or varnish applied thereto.
5. An imperforate sack formed of fabric and metallic members woven into a cloth, 55 and having an internal and external coating of enamel applied thereto.
6. An imperforate sack formed of fabric and copper wire members woven into a cloth and having an internal and external 60 coating of enamel applied thereto.

In testimony whereof, I have hereunto set my hand at Los Angeles, California, this 21st day of November, 1914.

ALVIN A. DAUGHERTY.
